UNITED STATES PATENT OFFICE.

HORACE D. CHIPMAN, OF CINCINNATI, OHIO.

RAPID-ACTING VISE.

SPECIFICATION forming part of Letters Patent No. 703,765, dated July 1, 1902.

Application filed March 8, 1902. Serial No. 97,216. (No model.)

To all whom it may concern:

Be it known that I, HORACE D. CHIPMAN, a citizen of the United States, residing at Cincinnati, in the county of Hamilton and State 5 of Ohio, have invented certain new and useful Improvements in Rapid-Acting Vises, of which the following is a specification.

My invention relates to a rapidly-operating vise.

10 The object of my invention is to produce a vise in which the jaws can be rapidly set at any desired distance apart by first a partial rotary backward movement of the screw-rod, which releases the engagement of the nut, and in that position the jaw, which is secured to 15 the screw-rod, may be readily moved longitudinally in either direction.

Another object of my invention is the construction of the parts in a simple manner, requiring very little machine-work, and so that 20 they can be cheaply made and yet strong and serviceable.

Another object of my invention is to produce a vise in which the screw-rod can be released from engagement with power-nut, still permitting the screw-rod to be continuously 25 revolved in either direction at will.

The various features of my invention will be more fully set forth in the description of 30 the accompanying drawings, forming a part of this specification, in which—

Figure 1 is a side elevation of my improved vise. Fig. 2 is an enlarged sectional elevation on line xx , Fig. 1. Fig. 3 is a central 35 longitudinal section of Fig. 1. Fig. 4 is an enlarged end elevation of nut-yoke frame and sector. Fig. 5 is an enlarged perspective view of sector-lifting cam and its sleeve. Fig. 6 is a perspective view of nut-yoke frame. Fig. 40 7 is a section on line vv , Fig. 3. Fig. 8 is a perspective view of one of the hinge half-nuts. Fig. 9 is a perspective view of the cam feather-key.

A represents the shell frame of the vise, the 45 opening serving as a guideway for the sliding jaw-arm. A' represents the base; A², the fixed jaw formed integral with the frame.

B represents a hollow jaw-arm sliding longitudinally in the hollow frame A. C represents 50 the movable jaw formed integral therewith.

D represents an inside frame supported

upon the base A' and rigidly secured thereto. The sides a of the shell frame B extend laterally each side of the frame D, so that the 55 jaw C and the extended arm B have a firm bearing-support to maintain the parallelism of the jaw.

Upon the frame D is mounted the operating mechanism for engaging and releasing the 60 operation of the nut with which the screw-rod E engages to apply power to the movable clamping-jaw. These operative parts are so constructed and combined that the screw-rod and its nut are always in engagement when 65 the screw-rod is turned forward and provided with devices whereby the engagement of the nut is automatically released during a portion of the backward revolution of the screw-rod, and during this period the jaw-arm is 70 free to be slid in either direction. This operation is secured by the following devices: F F' represent half-nuts, each of which is the counterpart of the other. They are pivoted by centers e to the bracket b of the frame D, as 75 shown in Fig. 3. These half-nuts in their normal position are closed, so as to engage with the threads of the screw-rod E, and they are in this position whenever the screw-rod is turned by a forward movement of the screw-rod. In order that these nuts may be disengaged by being opened outward, as shown in 80 dotted lines, Fig. 2, by a backward turn of the screw-rod and held in normal engagement with the threads of the screw-rod by a forward 85 turn, I provide the following devices: G represents a nut-yoke frame having two limbs f , projected downward and normally resting on the base of frame D. When in this position, the longitudinal arms d engage with the inclined shoulders c of the half-nuts F F' and hold the nut-limbs in engagement with the screw-rod. In order that the nut-limbs may 90 be swung outward to disengage the threads of the screw-rod, I provide the following mechanism for lifting the nut-yoke frame G and having it engage with the tripping-ears g on the half-nuts: h represents the catches on the limbs d , which engage with the tripping-ears g when the yoke-frame is lifted, thereby causing the nut-limbs to oscillate on their centers e and move outward far enough to be entirely 95 free from the threads of the screw-rod and to occupy the position shown in dotted line, Fig. 100

2. This nut-yoke frame is adapted to be lifted only by the backward turn of the screw-rod and during only a part of its revolution, but holds the nut-limbs in engaging position 5 always during the forward turn of the screw-rod. This result is obtained by the following instrumentalities: H represents a cam-disk. Upon the face of it is provided two cam members I I'. J represents a journal 10 boss or sleeve rigidly secured to the cam. This disk journals in the hub K of the frame D, projecting upward from the base of the frame D, as shown in Fig. 3. The sleeve J is provided with a half-slot L, as shown in Fig. 15 5. Screw-rod E is splined its entire length. M represents a feather-key provided with an oblong base or limb resting in the spline of the screw-rod. N represents the key portion projecting through the slot L of the cam-sleeve 20 J. This key revolves with the screw-rod and causes the rotation of the cam when the screw-rod is turned forward by the engagement of key N with the sides l l' of the slot. Upon the nut-yoke frame G and on its rear face 25 is pivoted a gravity-sector O. As the screw-rod E is turned forward this sector is pushed to one side, as shown in dotted lines, Fig. 4, and drops back by gravity as soon as the cams I I', respectively, pass the same. In 30 order to prevent the sector from being thrown too far, the rear face of the nut-yoke frame G is provided with a segmental slot n, and the sector with a pin m engages the said slot and limits its movement in each direction. 35 Now when the cam is reversed by turning the screw-rod backward one of the cams I I' comes in engagement with the face of said sector O when it is in the position opposite that shown in Fig. 4. The engagement of the 40 cam with the sector and its pin n lifts the nut-yoke frame upward, and during the last portion of its upward movement the frame-arms d engage the ears of the half-nuts and swing them outward far enough to release 45 the thread engagement. When in this position, the jaw C and its shell-arm may be freely moved in or out.

In order that the nut-release may be maintained for some little time, so that the screw-rod will not have to be turned back to an exact position, the cams and sector are constructed as follows: The ends of the cams are 50 arcs of a circle. The end of the sector O is the arc of a circle. The lengths of the cams and sector are so proportioned that when the sector has reached the end of its upward movement in lifting the yoke-frame G the periphery of the lifting-cam will engage with the periphery of the sector, and the cam will 55 travel past the sector and hold it up during the time of its engagement. As soon as the cam has traveled past the sector it will drop into position to be again lifted by the next cam. Thus the screw-rod may be turned 60 backward continuously, if desired. There is no locking of the parts during the backward turn of the screw-rod, and hence no strain in-

incident thereto, the vise-jaw being free to be slid laterally during any period of the cam-and-sector contact.

The screw-rod E is secured to the movable jaw C by a gib s. Pressure to pull or push the screw-rod causes the jaw and screw-rod to slide freely in and out of the stationary vise-frame, thereby adjusting the relative position of the vise-jaws to any desired distance apart. The instant the screw-rod is turned to the forward position the engagement of the cam and sector is released. The weight of the nut-yoke frame G causes it to descend, 75 and in its descent engages the inclines c of the half-nuts, forcing them together and causing their threads to quickly engage with the threads of the screw-rod.

Mode of operation: Q represents the usual handle journaled in the stem of the screw-rod, as in ordinary vises. Suppose the parts to be in their normal position, with the threads of the half-nuts engaging with the screw-rod. A forward turn of the screw-rod draws the 80 jaw C inward toward the clamping position. If now it be desired to move the jaw C longitudinally, the screw-rod is turned in the reverse direction. When the lug N of the feather-key has turned backward far enough 85 to engage with the face l' of the slotted sleeve J, the cams I I' would be rotated backward, engaging the edge of the sector, forcing it to raise the nut-yoke frame G and swing the half-nuts outward, freeing them from the 90 screw-rod, permitting the screw-rod and the jaw C to be freely moved longitudinally for 95 adjusting of the relative position of the jaws. A partial turn of the lever Q will bring the half-nuts into engagement for moving the 100 jaw C by screw-power. I extend the slot L in the sleeve J approximately a half-revolution, so that a backward turn of the screw-rod will allow the front jaw to recede a sufficient distance to release the clamping pressure before the nut is free, thereby allowing 105 the work to be released from the jaws before the power-nut is set free. The side of the elongated slot gives a sufficient movement of 110 the sector to allow the cams to pass freely. 115

I use two cams, so that the backward turn of the screw-rod will not be so great to release the half-nuts as would be required with only one cam.

It will be observed that the parts are so 120 constructed that very little machine-work is required to fit the parts of the vise together, and yet the parts are heavy, strong, and durable and capable of resisting the strains to which a vise is subjected.

Having described my invention, I claim—

1. In a vise employing a movable jaw journaled in the frame supporting the stationary jaw, a screw-rod, half-nuts in normal engagement with the screw-rod, a nut-frame 130 normally engaging the said half-nuts, lifting mechanism composed of a cam, the combination of a sector and a key operated by the screw-rod adapted to lift the nut-frame and 135

free the nut engagement by the backward turn of the screw-rod, substantially as specified.

2. In a vise employing a stationary jaw, a sliding jaw supported in the vise-frame, a power-nut composed of segmental half-nuts pivoted to the frame of the vise, in combination with a nut-frame having limbs normally engaging the half-nuts and locking them in position, and swinging said half-nuts by the lifting of the nut-frame, substantially as specified.

3. In combination with the screw-rod of a vise secured to a movable jaw and half-nuts pivotally attached to the vise-frame, a nut-frame adapted to engage the half-nuts and hold them in the closed or open position, a lifting mechanism composed of a sector pivoted to the nut-frame, a cam having a key feathered engagement with the screw-rod, the sector and cam being so disposed that the sector will be swung laterally by the cam engagement during the forward revolution of the screw-rod and will engage and lift the sector during a part of the backward revolution of said screw-rod, substantially as specified.

4. In a vise, a nut-releasing mechanism composed of a cam having a slotted sleeve encompassing a screw-rod, a sector pivoted to a nut-releasing frame, a feather-key adapted to connect the screw-rod with the cam-sleeve, the parts being so disposed that the sector will swing idly during the forward turn of the screw-rod and come into snapping engagement with the cam by the backward turn of the screw-rod, substantially as specified.

5. In a vise employing a lifting-sector, a cam for operating the same provided with means for periodical engagement with a screw-rod, the said sector being pivoted in the path of the traveling cam, the peripheries of said sector and cam being arcs of a circle adapted to engage each other, substantially as herein specified.

6. In a vise, the combination of a fixed and a sliding jaw, an operating-screw, a housing

within the sliding jaw containing two half-nuts pivoted from above so as to normally fall together by gravity upon the contained operating-screw, a vertically-movable frame engaging the opposite sides of the half-nuts exteriorly, said frame being normally seated by gravity, to clamp said half-nuts on the screw, and when lifted to separate said half-nuts therefrom, a cam-sleeve on said screw adapted to turn therewith, and connections between said sleeve and frame adapted to be actuated by the reverse rotation of the screw to lift said frame, whereby the sliding jaw may be adjusted without the screw, substantially as specified.

7. In a vise the combination of a fixed and sliding jaw, an operating-screw, a housing in the sliding jaw containing movable half-nuts for engaging the screw, a sliding frame straddling the half-nuts adapted to clamp the nuts to the screw and release the nuts therefrom, a cam-sleeve on the screw, tripping devices between said frame and cam-sleeve whereby the said frame is raised at a point in one direction of rotation of the screw, a peripheral keyway in the cam-sleeve and a key on the screw engaging said way, whereby the operating-screw may be given a part rotation within said cam-sleeve before the cam-sleeve is caused to rotate therewith, substantially as specified.

8. In a vise, a screw-rod, a cam-sleeve on the screw-rod, a key on the said screw-rod, a peripheral slotted keyway in the said sleeve allowing the said screw-rod when its direction of rotation is reversed to travel a part of one revolution independent of said sleeve, and half-nuts adapted to engage said screw-rod and to be actuated by the said cam, substantially as described.

In testimony whereof I have hereunto set my hand.

HORACE D. CHIPMAN.
